(57) **CLAIM**

The ornamental design for the photoelectric energy transducing apparatus, as shown and described.

DESCRIPTION

FIG. 1 is a perspective view of a photoelectric energy transducing apparatus showing our design;

FIG. 2 is another perspective view thereof;

FIG. 3 is a front view thereof;

FIG. 4 is a rear view thereof;

FIG. 5 is a left view thereof;

FIG. 6 is a top view thereof; and,

FIG. 7 is a bottom view thereof; the right elevation view thereof being a mirror image of the left; the broken lines illustrate portions of the photoelectric energy transducing apparatus that forms no part of the claimed design.
